HONING MACHINE

Wilson P. Hunt, Moline, Ill., assignor to Moline
Tool Company, Moline, Ill., a corporation of
Illinois

Application November 15, 1946, Serial No. 710,164

12 Claims. (Cl. 51—34)

1

The invention relates to an improved hone and honing machine.

More specifically, the invention relates to an improvement in machines adapted to hone internal cylindrical bores such as those in automobile cylinder blocks which permit stones carried in a honing head to be moved outward an adjustable distance into contact with the cylinder wall and then fed out slowly as metal is ground away and the stones wear while the head is revolving and reciprocating lengthwise of the bore.

The invention contemplates a hone construction wherein two cones are automatically moved axially of the hone to feed the stones out during the honing operation while providing independent adjustments for each cone which permit the operator to expand either end more than the other should one end of the stones wear faster than the other.

One object of the invention is to provide a honing head containing two cones axially movable in the honing head and adapted to spread the stones.

Another object is to provide a honing head containing two cones, each axially movable independent of the other, each adapted to spread one end of the stones in the hone.

Another object is to provide a honing head containing two cones, each axially movable independent of the other, with means permitting moving each cone while the hone is revolving and reciprocating.

Another object of the invention is to provide a honing head containing two cones, concentric axially movable elements for moving the cones, an automatic cam mechanism for moving each axially movable element while permitting manually modifying the movement of either cone independent of the other.

Another object of the invention is to provide means for automatically expanding the stones in a hone during honing at a rate which varies, very fast during the first strokes, slower after that, with a period during which the stones do not expand at all and finally start contraction of the stones.

The invention thus provides means for spreading the stones in a manner to correct for unequal wear at opposite ends of the stones. This is apt to occur in honing cylinder walls of a non-uniform section such as closed end aeroplane cylinders.

Fig. 1, partly in section, is an elevation of a honing machine equipped with the improved hone shown in sectional elevation.

Fig. 2 is a front view of the spindle shown in Fig. 1.

2

Fig. 3 is a partial top view taken along line 3—3 in Fig. 1.

Fig. 4 is a section taken along line 4—4 in Fig. 1.

1 **1** is a cross rail of a honing machine of conventional design. This cross rail slides in vertical guides carried by housing 15 which rises from a bed or table 17. This cross rail alternately moves up and down relative to the table. It is 10 customarily moved by a hydraulic cylinder, not shown, placed inside the housing. The cross rail 1 may carry finger 31 which engages adjustable fingers 33, 35 which are mounted adjustably on a control rod 37 when the cross rail reaches 15 the end of its up or down stroke. When thus engaged the control rod is moved and this causes the cross rail moving mechanism to reverse its movement. The work to be honed is shown at 19 as a sleeve supported on the table in any conventional manner. It may be held in a holder 21 having a bottom flange by clamps 23 tightened down by screws 25 in the holder. The holder may have a flange 27 which slidably supports it on the table and the holder may extend 25 down into an opening 29 in the table, the opening being of larger diameter than the sleeve so that the sleeve holder may be aligned with the axis of the hone. After the work has been properly centered it may be bolted to table 17 by bolts 30 22.

When honing is completed the cross rail is moved up beyond stop 33.

The cross rail carries a horizontal drive shaft 4 which carries a spiral gear 3 which meshes with 35 another spiral gear 5. This spiral gear 5 transmits rotary motion to a spindle 6 rotatably supported in the cross rail 1. This spindle carries at its lower end a cage-shaped honing head 7. This head is also of conventional design and carries four radially movable stone holders 8. Each stone holder carries pins 9 and 10 which extend through openings in the head 7, preventing vertical or circumferential movements of the stone holder relative to the head. A long, narrow stone 11 is mounted in each stone holder. A coiled garter spring 18 extends around the head 7 and engages the upwardly extending ears 20 of each stone holder. The spring thus tends to draw the upper ends of all the stone holders inward. A coiled garter spring 30 is adapted to draw together the lower ends of the stone holders.

A sleeve 12 is free to slide up and down inside the spindle 6 which is hollow. This sleeve carries at its lower end a cone 14. This cone contacts wedge-shaped surfaces 16 on the pins 9 which are attached to the upper ends of the stone holders. The cone 14 is adapted to push the stones outward overcoming the spring 18 when

the sleeve 12 is moved downward inside spindle 6.

A rod 24 extends through the sleeve 12. At its lower end this rod carries a cone 26 which bears against the wedge-shaped surfaces 28 of the pins 10 connected with the lower ends of the stone holders.

Thus it will be seen that the stone holders always tend to move radially inward impelled by the springs 18 and 30 but can be moved outwardly by moving cones 14 and 26 downward. These cones may be moved downward automatically equal amounts to correct for the removal of part of the surface being honed and the wearing away of part of the stone when that wear is uniform throughout the length of the stone.

But it will be obvious that this arrangement also provides means for moving one end of the stones manually outward faster than the other. In this manner increased wear on one end of the stone caused by conditions peculiar to the work being honed can readily be corrected.

It should be noted that this can either be accomplished by giving the two cones 14 and 26 the same slope and moving them different distances or by giving the two cones different slopes and moving them the same distances. In the latter case, if the rod 24 and the sleeve 12 move together the two ends of the stones will automatically be spread amounts which bear a fixed relation to each other.

To support the mechanism which moves rod 24 and sleeve 12 the cross rail 1 may have upwardly extending posts 40 which support two horizontal rock shafts 42 and 44. Clamped to the rock shaft 42 is an arm 46 and clamped to shaft 44 is an arm 48. The arm 48 carries a micrometer screw 50 which bears upon the enlarged head 52 of rod 24. A compressed spring 54 surrounds a part of rod 24. The upper end of the spring bears against the lower surface of the enlarged upper end 52 of rod 24 and its lower end against shoulder 56 in sleeve 12. Obviously, the spring 54 will tend to lift the rod 24 with its attached cone 26 against the micrometer screw 50 which limits its upward motion. Thus, by changing the setting of micrometer screw 50 the spread of the lower ends of the stones 11 can be altered.

Riding loose on shaft 42 is a lever 60. An opening 62, considerably larger than rod head 52, extends through lever 60. This lever 60 has two downwardly extending projections 64, one on each side of the opening. These projections bear upon a thrust washer 66 supported on balls free to rotate on a flange 67 which forms the upper end of the sleeve 12. A spring 68, which is considerably heavier than the spring 54, bears against flange 67 tending to lift the thrust bearing together with sleeve 12. The arm 46 carries a micrometer screw 70 which bears upon the outer end of the lever 60. It is clear that by turning the micrometer screw 70 the lever 60 can be moved and that the lever 60 will move the sleeve downward relative to spindle 6, and that this will spread the upper ends of the stones 11.

Thus, means have been provided whereby the operator can correct for different degrees of wear of the upper and lower ends of the stones. The micrometer screw 70 may have a coarser thread than the screw 50 since the distance point 64 moves is less than the distance the outer end of the lever 60 travels. In this manner one turn of each micrometer screw will represent the same vertical movement of the cones 14 and 26 and the

same radial movement of the stones. However, the slope of the two cones can be so selected that if the micrometer screws 50 and 70 have the same pitch the two ends of the stones will still be spread the same amount.

It will be understood that a single cross rail may carry several spindles, all duplicates of the one described. The shafts 4, 42, 44, in that event all extend past all of the spindles so that whatever mechanism is provided to turn these shafts will turn all the spindles, spread the top of all stones equal amounts, and likewise spread the bottoms of all stones on all the honing heads equally.

In the manual adjustment just described the arms 46 and 48 remain stationary while the sleeve 12 and rod 24 are moved by the micrometer screws.

The invention also provides for automatically moving the stones in each head radially outwardly from their initial position while honing at a rate which will correct for the wearing away of the stones and for the increased diameter of the bore as material is removed from the surface being honed. This is accomplished by automatically moving arms 46 and 48. Upon completion of the honing of one cylinder the arms resume their initial positions and the stones are automatically brought back to their initial position clear of the surface honed. It is now only necessary for the operator to move the micrometer screws 50 and 70 before honing on the next piece by the amount required to offset the wear of the stones which took place during the previous operation to make the hone ready to start work on the new cylinder with the stones in the same condition as they were when honing the previous sleeve.

The stones are automatically moved outward in the head the proper amounts at the proper times as the honing operation progresses, by turning the shafts 42, 44 which carry arms 46, 48 appropriate amounts. This causes the arms 46, 48 to move the micrometer screws 50 and 70 down on rod 24 and sleeve 12 respectively and these in turn move cones 26, 14 which spread the stones.

To produce this outward movement of the stones in the honing head during each honing operation and withdrawing the stones thereafter, the shafts 42, 44 carry arms 72, 74 respectively. At the outer ends of these arms followers 76, 78 respectively are held in contact with two cams 80, 82 respectively. Each of these cams turns with shaft 84 which also carries a ratchet 86. The shaft 84 is supported on an upward extension 88 of the cross rail 1.

Both of these two cams are generally involute in form but do not necessarily have the same rise. Each of these cams has a radial drop 90, 92 respectively. It will be clear that (Fig. 1) if the shaft 84 is slowly turned in a counterclockwise direction, each of the followers 76, 78 will follow its own cam 80, 82, and the shafts 42, 44 will be turned in a counterclockwise direction until the radial drop 90, 92 of the cam is reached at the end of the honing operation. Then the two arms 72, 74 will jump back in a clockwise direction to their original position, thereby allowing the garter springs to contract the stones.

These cams may be shaped to give practically any control of stone advance desired, but ordinarily they are shaped to expand the stones rapidly during the first stroke or two to secure contact between the stones and the bore, then to expand gradually and uniformly, step by step,

until the portion of the cam which corresponds to the desired size of bore is reached. After that the follower traverses a cylindrical portion of the cam giving a dwell during one or more strokes of the spindle without further expansion of the stones. During this period the pressure on the stones drops off and the stones are said to "stroke themselves out." The drop is reached just before or during the withdrawal stroke and the hone is contracted.

The two cams may be so designed that the upper and the lower ends of the stones are fed outward according to a different pattern or to different degrees. Thus, if in honing a particular type of sleeve the lower end of the stone must do more work than the upper, the cam 82 may have a larger rise than the cam 80 which controls the spread of the upper end of the stone.

Upon completion of the honing operation the upward pressure of the springs 54 and 68, acting on all of the spindles, will press arms 46 and 48 upward and thus will bring cam followers 76, 78 back into the position shown.

To secure the uniform slow motion of shaft 84 the arm 96 is loosely movable thereon. This carries a pivot 98 on which a ratchet arm 100 is pivoted. A vertical rod 102 freely movable in a stationary part 2 carried by the housing of the machine has a collar 104 adjustably secured to the vertical rod. As the cross rail 1 moves up and down the collar 104 will, upon each down stroke, engage part 2 causing the ratchet to move forward one or several notches carrying with it the cams 80, 82. On the up-stroke the weight of rod 102 and collar 104 will turn the arm 96 downward again until the arm 96 rests on a pin 105 carried by the extension 88.

Operation.—In honing a cylindrical bore the cylinder block 19 is fastened into holder 21 resting on the fixed table 17 of the machine and vertical reciprocation of the cross rail 1 is started. Continuously running shaft 4 through the spiral gears 3, 5 turns spindle 6 and the hone. The first down stroke of the cross rail brings the hone down into the bore to be honed after which it reciprocates with a stroke determined by setting fingers 33, 35 to bring the ends of the stones slightly past the ends of the bore at each stroke. During the first few down strokes ratchet 86 moves the cams 80 and 82 so that followers 90, 92 pass over the "quick rise" portion of the cam, bringing the stones in contact with the bore. Then each succeeding stroke brings arms 46, 48 a little lower and this expands the stones a little more until the cylindrical part of the cams is reached. By this time the bore should be honed to size and this gives the stones a chance to make their final strokes under decreasing pressure. The stones are then contracted by the follower riding over the cam. In the last stroke the cross rail rises higher and the hone is also withdrawn from the bore. It stops in the "up" position so that the cylinder may be removed and another placed in the bed. A coolant is supplied while the hone is in operation through a pipe, not shown, and this coolant also washes away the particles removed from the bore by the hone.

After the cylinder has been removed and a new piece put in place the operator, knowing how much the stone is worn down by each piece honed, moves the micrometer screws 50 and 70 the amounts necessary to provide the proper correction for the amount worn off the surfaces

of the stones during the previous honing operation. By moving these two micrometer screws unequally the operator can correct for any greater wear that may take place upon one end 5 of the stone than the other.

What I claim is:

1. In a honing machine, a vertical frame, a cross rail slidably mounted on said frame, a vertical tool spindle rotatably supported on said cross rail, a honing tool having a cylindrical body supported on said spindle, abrasive stones supported in said cylindrical body, means located at one end of the cylindrical body for spreading one end of each stone radially outward, a rod extending through said tool spindle for actuating said stone spreading means, a second means for spreading the other end of each stone located at the other end of the cylindrical body, a sleeve extending through said tool spindle and surrounding said rod for actuating said second stone spreading means, means on said cross rail including a shaft carrying a cam having successive portions with a rapid rise, a gradual rise, a dwell, and a drop adapted to engage said rod and another cam adapted to engage said sleeve for progressively spreading said stones by moving the rod and sleeve axially in the tool spindle and means connected to the frame for moving the shaft and cams at each reciprocation 30 of the cross rail on the frame.
2. In a honing machine, a vertical frame, a cross rail slidably mounted on said frame, a vertical tool spindle rotatably supported on said cross rail, a honing tool having a cylindrical body supported on said spindle, abrasive stones supported in said cylindrical body, means located at one end of the cylindrical body for spreading one end of each stone radially outward, a rod extending through said tool spindle for actuating said stone spreading means, a second means for spreading the other end of each stone located at the other end of the cylindrical body, a sleeve extending through said tool spindle and surrounding said rod for actuating said second stone spreading means, means on said cross rail including a shaft carrying a cam having successive portions with a rapid rise, a gradual rise, a dwell, and a drop adapted to engage said rod and another similar cam adapted to engage said sleeve for progressively moving said stones radially by moving the rod and sleeve axially in the tool spindle so that when the honing machine is started after the hone has been inserted in the bore of a piece to be honed the stones will be moved rapidly into contact with the walls of the bore, then fed gradually as the honing proceeds, then held in radial position while the stones stroke out and are finally allowed to recede on completion of the honing, and means connected to the frame for moving the shaft and cams at each reciprocation of the cross rail on the frame.
3. A honing machine having a table, a vertical frame, a cross rail vertically movable on said frame, a rotatable vertical hollow spindle supported by said cross rail, a cylindrical hone body carried by the vertical hollow spindle, abrasive stones carried in the hone body, first means for moving the upper ends of all the stones radially outward, a second means for moving the lower ends of all the stones radially outward, a sleeve in the hollow spindle engaging said first means for moving the upper ends of all the stones, a first spring bearing against the sleeve and the spindle tending to elevate the sleeve, a rod in the

70
75

sleeve engaging said second means for moving the lower ends of all the stones, a second spring bearing against the sleeve and the rod tending to elevate the rod relative to the sleeve, mechanism carried by the cross rail for depressing the sleeve against the first spring, a second mechanism carried by the cross rail for depressing the rod against the second spring, cams mounted on a shaft supported on said cross rail, each cam controlling the position of one of said mechanisms, a ratchet wheel mounted on the cam shaft, a pawl actuated by the movement of the cross rail relative to the table to advance the cam shaft step by step, rock shaft assemblies carried by the cross rail, each rock shaft assembly including a follower which is engaged by one of said cams and an arm, the arm of one assembly tending to depress the rod against the second spring while the arm of the other assembly tends to depress the sleeve against said first spring.

4. In a honing device, a table adapted to support work having bores to be honed, a number of spindles adapted to enter said bores, a cross rail supporting said spindles and adapted to move said spindles into and out of said bores, a driving shaft assembly supported on the cross rail and adapted to rotate all of said spindles, a honing head carried by each spindle, stones supported in a radially movable manner in each of said heads, a sleeve axially movable in each spindle, a cone located within the hone body attached to said spindle adapted to spread one end of each stone radially, a rod axially movable inside said sleeve, a second cone located within the hone body attached to said rod and adapted to spread the other end of each stone radially, a rock shaft carried by the cross rail, rocker arms attached to the rock shaft adapted to move the sleeve relative to the spindle, a second rock shaft carried by the cross rail, other rocker arms attached to the second rock shaft adapted to move the rod relative to the spindle, mechanism supported on the cross rail including a single pair of cams each cam adapted to turn one rock shaft and its set of rocker arms, means responsive to the reciprocation of the cross rail toward and from the table to turn the cams step by step.

5. In a honing machine, in combination, a vertical frame, a cross rail mounted on said frame and vertically movable thereon, a hollow honing spindle supported on said cross rail, a hone body supported on the lower end of the spindle, stones radially movable in the hone body, means tending to draw the stones inward toward the center of the hone body, means including a rod extending down through the spindle to spread said stones, means on the cross rail adapted to rotate the spindle, a coil spring reacting against said spindle and a collar on the rod, a thrust bearing resting against the collar, a lever pivoted on the cross arm bearing on the thrust bearing, a second lever pivoted on the cross rail bearing against the first lever, a shaft on the cross rail carrying a ratchet and a cam which bears against the second lever, a device engaging the vertical frame adapted to move the ratchet one step at each movement of the cross rail on the frame.

6. In a honing machine, in combination, a vertical frame, a cross rail mounted on said frame and vertically movable thereon, a hollow honing spindle supported on said cross rail, a hone body supported on the lower end of the spindle, stones radially movable in the hone body, means tending to draw the stones inward toward the center of the hone body, means including

a rod extending down through the spindle to spread said stones, means on the cross rail adapted to rotate the spindle, a coil spring reacting against said spindle and a collar on the rod, a thrust bearing resting against the collar, a lever pivoted on the cross arm bearing on the thrust bearing, a second lever pivoted on the cross arm and carrying a manually adjustable screw which bears against the first lever, a shaft on the cross rail carrying a ratchet and a cam bearing against the second lever, a device engaging the vertical frame adapted to move the ratchet one step at each movement of the cross rail on the frame.

7. In a honing machine, a vertical frame, a cross rail mounted on said frame and adapted to reciprocate up and down on said frame, a vertical tool spindle rotatably supported on said cross rail, a honing tool having a cylindrical body supported on said spindle, abrasive stones supported in a radially movable manner in said cylindrical body, means located at one end of the cylindrical body for moving one end of each stone radially outward, a first rod extending down through said tool spindle for actuating said stone spreading means, a second means located at the other end of the cylindrical body for moving the other end of each stone radially outward, a second rod extending through said tool spindle for actuating said second stone spreading means, two mechanisms mounted on the cross rail, each mechanism adapted to move one of said rods respectively, a shaft supported on the cross rail, a cam carried by said shaft and adapted to move one of said mechanisms, a second cam carried by said shaft and adapted to engage the other of said mechanisms, a ratchet disc also carried by said shaft, a pawl coacting with said ratchet disc, means actuated by the reciprocation of the cross rail on said frame to actuate said pawl.

8. In a honing machine, a vertical frame, a cross rail mounted on said frame and adapted to be reciprocated up and down on said frame, a vertical tool spindle rotatably supported on said cross rail, a honing tool having a cylindrical body supported on said spindle, abrasive stones supported in a radially movable manner in said cylindrical body, means located at one end of the cylindrical body for moving one end of each stone radially outward, a rod extending through said tool spindle for actuating said stone spreading means, a second means located at the other end of the cylindrical body for moving the other end of each stone radially outward, a sleeve extending through said tool spindle and surrounding said rod for actuating said second stone spreading means, two mechanisms mounted on the cross rail engaging respectively said rod and said sleeve, a shaft supported on the cross rail, a cam carried by said shaft and adapted to move one of said mechanisms, a second cam carried by said shaft and adapted to engage the other of said mechanisms, a ratchet disc also carried by said shaft, a pawl coacting with said ratchet disc, means actuated by the reciprocation of the cross rail on said frame to actuate said pawl.

9. In a honing machine in which after the hone is inserted in the bore of a piece to be honed the stones will be moved rapidly into contact with the walls of the bore then moved outward gradually as the honing proceeds then held in radial position while the stones stroke out and finally allowed to recede on completion of the honing, a vertical frame, a cross rail mounted on said frame and adapted to reciprocate up and down on said frame, a vertical tool spindle rotat-

ably supported on said cross rail, a honing tool having a cylindrical body supported on said spindle, abrasive stones supported in a radially movable manner in said cylindrical body, means located at one end of the cylindrical body for moving one end of each stone radially outward, a rod extending through said tool spindle for actuating said stone spreading means, a second means located at the other end of the cylindrical body for moving the other end of each stone radially outward, a sleeve extending through said tool spindle and surrounding said rod for actuating said second stone spreading means, two mechanisms mounted on the cross rail engaging respectively said rod and said sleeve, a shaft supported on the cross rail, a cam having a gradual rise, a dwell, and a drop carried by said shaft and adapted to move one of said mechanisms; a second cam carried by said shaft having a gradual rise, a dwell and a drop and adapted to engage the other of said mechanisms; a ratchet disc also carried by said shaft, a pawl coacting with said ratchet disc, means actuated by the reciprocation of the cross rail on said frame to actuate said pawl, and manually actuatable means carried by each of said mechanisms for moving the rod and sleeve endwise independent of said cams to correct the position of said stone for stone wear during a preceding honing operation.

10. In a honing machine, a vertical frame, a cross rail mounted on said frame and adapted to reciprocate up and down on said frame, a vertical tool spindle rotatably supported on said cross rail, a honing tool having a cylindrical body supported on said spindle, abrasive stones supported in a radially movable manner in said cylindrical body, means located at one end of the cylindrical body for moving one end of each stone radially outward, a sleeve extending through said tool spindle which when depressed actuates said stone spreading means, a first spring bearing against said sleeve and said spindle tending to elevate the sleeve, means located at the other end of the cylindrical body for moving the other end of each stone radially outward, a rod extending through said sleeve which when depressed actuates said last named stone spreading means, a second spring bearing against the sleeve and the rod tending to elevate the rod relative to the sleeve, two mechanisms mounted on the cross rail to depress respectively said rod and said sleeve, a shaft supported on the cross rail, a cam adapted to move one of said mechanisms, a second cam carried by said shaft and adapted to engage the other of said mechanisms, a ratchet disc also carried by said shaft, a pawl coacting with said ratchet disc, means actuated by the reciprocation of the cross rail on said frame to actuate said pawl to move said disc and thereby cause said sleeve and rod to be depressed to spread the ends of said stone.

11. In a honing machine, a vertical frame, a cross rail mounted on said frame and adapted to reciprocate up and down on said frame, a vertical tool spindle rotatably supported on said cross rail, a honing tool having a cylindrical body supported on said spindle, abrasive stones supported in a radially movable manner in said cylindrical body, means located at one end of the cylindrical body for moving one end of each stone radially outward, a sleeve extending through said tool spindle which when depressed actuates said stone spreading means, a first spring bearing against said sleeve and said spindle tending to elevate the sleeve, means located at the

other end of the cylindrical body for moving the other end of each stone radially outward, a rod extending through said sleeve which when depressed actuates said last named stone spreading means, a second spring bearing against the sleeve and the rod tending to elevate the rod relative to the sleeve, two mechanisms mounted on the cross rail to depress respectively said rod and said sleeve, a shaft supported on the cross rail, a cam adapted to move one of said mechanisms, a second cam carried by said shaft and adapted to engage the other of said mechanisms, a ratchet disc also carried by said shaft, a pawl coacting with said ratchet disc, means actuated by the reciprocation of the cross rail on said frame to actuate said pawl to move said disc and thereby cause said sleeve and rod to be depressed to spread the ends of said stones, and micrometer screws carried by each mechanism to move said rod and sleeve to permit the initial relative axial adjustment of rod, sleeve, and the vertical hollow spindle.

12. In a honing machine, a vertical frame, a cross rail mounted on said frame and adapted to reciprocate up and down on said frame, a vertical tool spindle rotatably supported on said cross rail, a honing tool having a cylindrical body supported on said spindle, abrasive stones supported in a radially movable manner in said cylindrical body, means located at one end of the cylindrical body for moving one end of each stone radially outward, a sleeve extending through said tool spindle for actuating said stone spreading means when depressed, a first spring bearing against the sleeve and the spindle tending to elevate the sleeve, means located at the other end of the cylindrical body for moving the other end of each stone radially outward, a rod extending through said sleeve for actuating stone spreading means when depressed, a second spring bearing against the sleeve and the rod tending to elevate the rod relative to the sleeve, two levers pivoted on the cross rail to depress respectively said rod and said sleeve against said springs, a shaft supported on the cross rail, a cam adapted to move one of said levers, a second cam carried by said shaft and adapted to move the other of said levers, a ratchet disc also carried by said shaft, a pawl coacting with said ratchet disc, means actuated by the reciprocation of the cross rail on said frame to actuate said pawl to move said cams, a manually adjustable screw carried by one lever engaging said sleeve, and a manually adjustable screw carried by the other lever engaging said rod.
